(57) **CLAIM**

The ornamental design for a mosquito lamp, as shown and described.

DESCRIPTION

FIG. 1 is a front elevation view of the mosquito lamp showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a rear perspective view thereof.

The broken lines throughout the drawing figures depict portions of the Mosquito lamp that form no part of the claimed design.
